CLAIM

The ornamental design for a light strip, as shown and described.

DESCRIPTION

FIG. 1 is a perspective view of a light strip showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the light strip shown in use. The broken lines in the drawings depict portions of the light strip that form no part of the claimed design. The broken lines in FIG. 8 represent environmental structure and form no part of the claim thereof.

1 Claim, 8 Drawing Sheets
